UNITED STATES PATENT OFFICE

155,325

DESIGN FOR A BOOK END LAMP BASE OR SIMILAR ARTICLE

Charles M. Wade, Colorado Springs, Colo.

Application April 23, 1949, Serial No. 2,206

Term of patent 14 years

(Cl. D48—20)

To all whom it may concern:

Be it known that I, Charles M. Wade, a citizen of the United States, residing at Colorado Springs, State of Colorado, have invented a new, original, and ornamental Design for Book End Lamp Base or Similar Article, of which the following is a specification, reference being had to the accompanying drawing, forming part thereof, wherein

Figure 1 is a perspective view of a book end lamp base or similar article, showing my new design.

Figure 2 is a side elevation of the same.

Figure 3 is a front elevation of the same.

The dotted lines in the drawing indicating a standard and lamp socket are for illustrative purposes only.

I claim:

The ornamental design for a book end lamp base or similar article, as shown and described.

CHARLES M. WADE.
